CLAIM

The ornamental design for a scale, as shown and described.

DESCRIPTION

FIG. 1 is a front perspective view of a scale, showing my new design;

FIG. 2 is a use state view thereof;

FIG. 3 is an open state view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The dashed broken lines depict portions of the scale that form no part of the claim.
